DESIGN FOR A SPARK-PLUG-CONDITION CHART HOLDER

Paul A. Schnebelen, Toledo, Ohio, assignor to
Hi-Speed Tire and Accessory Company, Toledo,
Ohio, a corporation of Ohio

Application December 4, 1939, Serial No. 88,664

Term of patent 14 years

To all whom it may concern:

Be it known that I, Paul A. Schnebelen, a citizen of the United States of America, residing at Toledo, Lucas County, Ohio, have invented a new, original, and ornamental Design for a Spark-Plug-Condition Chart Holder, of which the following is a specification, reference being had to the accompanying drawing, forming part thereof.

Fig. 1 is a perspective view of a spark-plug-condition chart holder, showing my design;

Fig. 2 is a top plan view; and

Fig. 3 is an end elevational view thereof.

I claim:

The ornamental design for a spark-plug condition chart holder, as shown.

PAUL A. SCHNEBELEN.
